UNITED STATES PATENT OFFICE.

WILLIAM PASSMORE, OF PONTIAC, MICHIGAN.

CURTAIN-FIXTURE.

1,294,698.

Specification of Letters Patent. Patented Feb. 18, 1919.

Application filed July 5, 1918. Serial No. 243,286.

To all whom it may concern:

Be it known that I, WILLIAM PASSMORE, a citizen of the United States, residing at Pontiac, county of Oakland, State of Michigan, have invented a certain new and useful Improvement in Curtain-Fixtures, and declare the following to be a full, clear, and exact description of the same, such as will enable others skilled in the art to which it pertains to make and use the same, reference being had to the accompanying drawings, which form a part of this specification.

My invention relates to curtain fixtures and an object of my improvement is to provide a simple, strong and efficient combination fixture that may be cheaply made and that shall serve to support both the curtain and shade.

I accomplish this result in the device illustrated in the accompanying drawings in which;

Figure 1 is a plan view of an apparatus embodying my invention secured in place, the shade roll and curtain pole being shown 25 adjusted to position.

Fig. 2 is a front elevation of the same, the shade roll and curtain pole and the support for the latter being shown in dotted lines.

Fig. 3 is a perspective view of a fixture 30 embodying my invention.

Fig. 4 is a side elevation of the same looking from one side, the holder for the curtain pole being shown adjusted to position.

Fig. 5 is a side view of the fixture looking 35 from the other side from that shown in Fig. 4, and

Fig. 6 is a plan view of the blank from which the fixture is formed.

Fig. 7 shows a modified form of the holder.

The fixture embodying my invention is 40 made entirely of sheet metal and consists of an arm *d* pressed out to form a concavo-convex portion *d*² at one end with a central aperture *d*³ therein for receiving the pintle 45 of the shade roll. At the other end of the arm there are lugs *e e* formed at the top and bottom edges and between these lugs is formed a tongue *f* which is bent around upon itself to form a vertically extending 50 socket *f*². *f*³ is a notch for positioning the curtain pole holding arm.

a represents the attaching surface for the fixtures. The fixtures are secured in the usual way with the pairs of lugs *e e* extending 55 toward each other and screws passing through the holes in said lugs. The tongue

rolled into the socket *f*² extends outward in the opposite direction to the lugs *e*. The slot *f*³ is cut in the upper edge of the tongue *f* at the upper and outer portion of the 60 socket *f*².

g is a curtain rod holder. This consists of a rod bent upward into a vertically upwardly extending portion *g*² at its outer end and a vertically downwardly extending portion *g*³ at its inner end. The portion *g*³ extends into the socket *f*² and fits therein. The horizontally extending portion drops into the notch *f*³ and is thereby held in its approximate position. The curtain rod *c* is 70 then put in position, the portions *g*² extending upward through vertical holes *c*² in the curtain rod.

Various forms of curtain rod holders may 75 be used instead of that above described and shown in Fig. 1. For instance, the form shown in Fig. 7 may be used where wooden curtain rods are employed. In this the rod *g* is bent to form a loop *g*^{2a} at its outer end and the wooden rod will rest in this loop, the outer portion of the loop extends vertically upward so that it may engage in a hole in the metal end as first above described, thus forming a combination part adapted to receive 80 both kinds of curtain rods, or the holder may be inverted and turned end for end, the part *g*² engaging in the socket *f*² and the part *g*³ engaging in the holder in the metal curtain rod end.

The fixture may be made in a machine by 85 a continuous operation. The blank is first cut out as shown at *f*⁵, the lugs *e e* are then turned at right angles to the arm *d* toward the convex side thereof and the tongue *f* is 90 bent in the other direction and rolled to form the socket *f*².

A slot *d*⁴ will be cut in one of each pair of fixtures to permit the pintle of the shade roll to be adjusted to place by a lateral 100 movement in the usual way.

What I claim is:

1. A sheet metal combined shade and curtain holder consisting of a blank cut from sheet metal presenting at one extremity a 105 head portion and at its other a rectangular extension, an intermediate laterally extended portion separated by cuts from said rectangular portion, said head being pressed into concavo convex form cut to provide a 110 socket for the shade roller, the rectangular portion being bent on itself to provide a

socket for the pole support, the lateral extension being bent at right angles to provide means for attaching the bracket to the window frame.

- 5 2. A sheet metal combined shade and curtain holder consisting of a blank cut from sheet metal presenting at one extremity a head portion and at its other a rectangular extension, an intermediate laterally extended portion separated by cuts from said rectangular portion, said head being pressed into concavo convex form cut to provide a

socket for the shade roller, the rectangular portion being bent on itself to provide a socket for the pole support, the lateral extension being bent at right angles to provide means for attaching the bracket to the window frame, the rectangular portion bent to extend to one side of the body and the lateral portion to the other side.

15 In testimony whereof, I sign this specification.

20 WILLIAM PASSMORE.
